UNITED STATES PATENT OFFICE.

HERMAN RAAB, OF NEW YORK, N. Y.

LOCK.

1,389,380.

Specification of Letters Patent. Patented Aug. 30, 1921.

Application filed March 1, 1920. Serial No. 362,463.

To all whom it may concern:

Be it known that I, HERMAN RAAB, a citizen of Austria, and a resident of Bronx, county of Bronx, and State of New York, have invented certain new and useful Improvements in Locks, of which the following is a specification.

The objects of the present invention are to provide a safe and secure lock mechanism designed to be operated by a key, but only by the one authorized to use such key.

One of the special features of the invention is the combination with the key operated part of the lock, of a permutation lock mechanism arranged to permit the use or operation of the key only after the permutation mechanism has been properly actuated.

In the accompanying drawing, I have illustrated the invention embodied in a practical and, at the present time, preferred form, but wish it understood that the invention is not limited to this particular disclosure, as will be apparent from the scope of the appended claims.

In the drawing referred to, Figure 1 is a broken sectional view of the lock with the permutation mechanism set against the entrance of the key.

Fig. 2 is a cross sectional view of the same taken on substantially the plane of line 2—2 of Fig. 1 but showing the permutation tumblers as set to admit the key.

Fig. 3 is a view similar to Fig. 1 but showing the key as having been entered in the lock and the cylinder as having been turned to release the lock mechanism.

Figs. 4, 5 and 6 are detached detail views of the three tumblers of the permutation lock mechanism.

The key plug in the lock illustrated is designated 10 and is shown as provided with a key slot 11 to receive the key 12 which is bitted to release the pin tumblers 13. At its inner end the key plug carries a roll-back 14 which may be of any usual or desired construction.

At the outer end of the key plug is mounted the permutation lock mechanism which is shown as having a finger hold or dial member 15 rotatably seated concentrically in the support or lock casing 16 about the key plug and arranged to operate through lost motion connections, a set of three locking disks or tumblers 17, 18 and 19 disposed within the same and arranged concentrically about the key plug. In the

illustration the lost motion operating connection is provided by a lug 20 on the inner periphery of the rotating finger hold designed to engage with the shoulders 21 and 22 provided on the first and second disks 17 and 18 and with a pin or shoulder 23 on the face of the third locking disk 19. The rotation of the dial in the proper order serves through the connections described to bring the three lock disks or tumblers into the positions indicated in Figs. 4, 5 and 6 with the slots 24, 25 and 26 in said tumblers all in registry.

When the tumblers are thus operated, the registration of the slots described forms a pocket to receive the outer end portion of a locking pin 27 carried by a spring 28 which is secured to the casing of the plug at 29, said pin being arranged to project through an opening 30 in said casing into the key slot in the plug. In Fig. 1, the pin is illustrated as thus projecting into the key slot and as being held in this condition by all three of the permutation disks to thereby lock the entrance of the key and to assist in locking the plug against rotation.

By reason of this construction, the key is prevented from being inserted into the key slot until the permutation mechanism has been operated in the proper combination.

In Figs. 2 and 3 I have shown how when the permutation tumblers are operated in the proper combination and the slots have thereby been brought into registration, the blocking pin 27 is free to be projected out of the key slot by the entering edge of the key and that when thus displaced from the key slot, the key plug is free to be turned by the key in the usual way. The spring 28 may be biased so as to automatically withdraw the key blocking pin as soon as the disks have been turned to the requisite combination.

To operate the lock mechanism, therefore, it will be seen requires both the possession of the right key and also a proper knowledge of the combination for which the permutation mechanism has been set. The lock is thus doubly safe-guarded and even one finding the key would be unable to unlock the lock without knowing the proper combination. On the other hand, one knowing the combination would be unable to operate the lock without the proper key. The invention is readily applicable to the steering mechanism or other parts of an au-

tomobile and when properly applied is secured against unlawful tampering.

What I claim is:

1. In a lock, a key plug, a key actuated tumbler or tumblers for securing said key plug, permutation elements and a locking pin controlling engagement of the key and key plug independently of the tumbler or tumblers, said locking pin being under control of the permutation elements aforesaid.
  2. In a lock, a key plug operable by a key, a key actuated tumbler or tumblers for securing said key plug, a set of permutation disks mounted concentrically about the key plug and a locking pin controlling engagement of the key and key plug, said locking pin being independent of the tumbler or tumblers and being controlled by the permutation disks.
  3. In a lock, a key plug operable by a key, a key actuated tumbler or tumblers for securing said key plug, a set of permutation disks mounted concentrically about the key plug, a locking pin controlling engagement of the key and key plug, said locking pin
- being independent of the tumbler or tumblers and being controlled by the permutation disks, said pin normally standing in the path of the key in the key plug and spring means for retracting said pin when the permutation disks are set at the proper combination.
4. In a lock, a key plug, a key actuated tumbler or tumblers for securing said key plug, permutation elements, a locking pin controlling engagement of the key and key plug independently of the tumbler or tumblers, said locking pin being under control of the permutation elements aforesaid, said permutation tumbler being in the front of a locking pin arranged to project into the path of the key in the key plug and a spring support for said locking pin tensioned to retract the pin from the path of the key when the permutation mechanism is set at the proper combination.

In witness whereof I have hereunto set my hand this 3rd day of February, 1920.

HERMAN RAAB.
